CARL HUBER, OF KARLSRUHE, GERMANY, ASSIGNOR TO GESELLSCHAFT FÜR HUBERPRESSUNG GESELLSCHAFT MIT BESCHRÄNKTER HAFTUNG OF KARLSRUHE, OF BADEN, GERMANY.

MEANS AND APPARATUS FOR MOLDING HOLLOW ARTICLES.

SPECIFICATION forming part of Letters Patent No. 731,367, dated June 16, 1903.

Application filed August 11, 1902. Serial No. 119,332. (No model.)

To all whom it may concern:

Be it known that I, CARL HÜBER, a citizen of Germany, residing at 38 Beiertheimer Allee, Karlsruhe, Baden, Germany, have invented 5 certain new and useful Improved Means and Apparatus for Molding Hollow Articles, (for which I have applied for a patent in Great Britain, dated January 16, 1902, No. 1,225,) of which the following is a specification.

10 This invention relates to the manufacture of hollow articles from a flat blank or plate by means of a flexible hollow pressing device filled with liquid, which I will term a "water-cushion" and which is so arranged and operated that it serves both as a drawing-tool for drawing the flat blank into a mold and also as the pressing-tool for pressing the drawn object into the required shape.

I will describe the apparatus which I employ for the purpose of my invention with 20 reference to the accompanying drawing, which represents a vertical section of the same.

The mold or matrix *m* for the hollow article to be produced, which is preferably formed of four separate parts, is contained in a coned outer casing upon which is laid the sheet-metal blank or plate *b*. This is held down upon the mold by a tubular holding device 25 *n*, which is provided with an annular water-cushion *k*, adapted to press upon the sheet-metal blank, while the plunger *p*, with its water-cushion *w*, effects the drawing operation.

30 The plunger *p*, which is subject to the pressure of the platen *a* of a hydraulic or other press, is of tubular form, so as to receive within it the tubular extension *w'* of the water-cushion *w*, which forms a flexible continuation of the plunger *p*. The tubular extension *w'* is open at the upper end for enabling the cushion *w* to be filled with liquid, the upper end of the plunger-bore being closed by a screw-plug *c* after the filling has been 35 effected.

The holding device *n* is movably connected to the upper flanged end of the plunger *p* by bolts *d*, on which are mounted helical springs *f*, whereby the downward pressure exerted

by the platen *a* upon the plunger *p* is transmitted in a yielding manner to the holder *n*, the arrangement being such that before the descent of the platen the springs *f* cause the holder *n* to project with its lower end somewhat below the lower end of the water-cushion *w*, so that as the platen and plunger descend the cushion *k* of the holder is first made to bear upon the blank *b*, so as to hold it before the plunger *p* and water-cushion *w* begin to draw the central part of the blank into 55 the mold. When by this operation the bottom of the cushion *w* is brought to bear against the bottom of the mold *m*, with the interposition of part of the drawn blank, then on the continuation of the downward motion 60 of the plunger the increasing pressure transmitted to all parts of the confined body of water in the cushion *w* will cause this to be bulged out laterally, whereby the drawn blank *b* will be expanded in a corresponding 65 manner, so as to assume the configuration of the mold *m* and of any ornamentation that may exist thereon. On the completion of the molding operation the plunger *p*, together with the water-cushion *w* and holder *n*, are 70 drawn upward again, so as to allow the molded hollow article to be removed from the mold.

The flexible water-cushion *w* can either be made of caoutchouc or of leather or other suitable flexible material that will withstand 80 the required pressure. When the apparatus is employed for molding articles out of a blank of celluloid or other material—such as pulverulent-horn, marble, and the like—that requires heat combined with pressure for 85 molding and consolidating it the water-cushion is heated by filling it with hot water or other suitable hot liquid.

Having thus described the nature of this invention and the best means I know of carrying the same into practical effect, I claim—

1. Apparatus for molding hollow articles from a flat blank consisting of the combination of a plunger, a flexible receptacle filled with liquid carried by said plunger, and a 95 tubular holding-down device surrounding the lower part of the plunger with the flexible receptacle and adapted to hold a flat blank upon

a mold while the plunger and flexible vessel descend for drawing and molding the blank, substantially as described.

2. Apparatus for molding hollow articles, consisting of the combination of a plunger, a flexible receptacle carried by said plunger, a tubular holding-down device surrounding the lower part of the plunger with the flexible receptacle and having a flexible cushion at its lower end adapted to be pressed down upon a flat blank and a spring connection between the upper end of the plunger and the holding-down device whereby this is pressed down upon the edges of the blank while the plunger and water-cushion effect the drawing and molding of the central part thereof, substantially as described.

3. An apparatus for molding hollow articles from a flat blank, comprising the combination with a plunger and mold, of a flexible receptacle containing a liquid and adapted to operate as a tool for drawing the blank into the mold and then acting as an expanding molding-tool for causing the drawn blank to assume the configuration of the mold, and means for suitably holding the blank upon a mold for the purpose set forth.

In testimony whereof I have hereunto set my hand in presence of two subscribing witnesses.

CARL HUBER.
